UNITED STATES PATENT OFFICE.

JAMES M. DODGE, OF PHILADELPHIA, PENNSYLVANIA, ASSIGNOR TO THE
EWART MANUFACTURING COMPANY, OF CHICAGO, ILLINOIS.

ELEVATOR-BOOT.

SPECIFICATION forming part of Letters Patent No. 355,514, dated January 4, 1887.

Application filed October 4, 1886. Serial No. 215,298. (No model.)

To all whom it may concern:

Be it known that I, JAMES M. DODGE, of Philadelphia, in the county of Philadelphia and State of Pennsylvania, have invented a new and useful Improvement in Elevator-Boots; and I do hereby declare that the following is a full, clear, and exact description thereof, reference being had to the accompanying drawings, making part of this application.

My invention relates to what are known as "elevator-boots," and has for its main object to provide for use a boot of a novel construction or conformation, in which the usual buckets of an elevator will work when handling any heavy and lumpy material with less liability of clogging and undue cramping of the buckets in the boot, and consequent injurious strain and wear on the buckets, chain, and gearing of the elevator.

Heretofore elevator-boots have been made (usually of metal) with the leading end of the boot—*i. e.*, that portion through which the loaded bucket ascends out of the boot, in a curved path of motion—expanded horizontally and longitudinally of the boot, so that by reason of the enlarged curve of the bottom of the boot at its leading end the filled buckets might more readily escape from or pass forwardly and upwardly out of the boot; but this provision for a more ready clearance or escape from the boot than if it were made the same at the portion through which the buckets pass forwardly and upwardly, as at the part through which the buckets pass down into the boot, (to fill,) has been found to be insufficient to avoid not infrequent jamming or clogging of the buckets in the boot and the consequent strain on and sometimes breakage of the buckets or the chains or the connections between the devices of the elevator.

It frequently happens, especially in handling coarse, lumpy, and hard material—such as coal or ores—that in passing up through the boot the bucket will crowd a lump of the material in between one of its own sides and one of the two usually vertical and parallel sides of the boot, and if the lump, while thus wedged in between the side of the boot and that of the traveling bucket, be of the usual

irregular shape and get turned so as to become forcibly wedged between the bucket and the boot, all the parts of the elevator machinery are of course subjected to undue strain, which sometimes causes serious injury to the machinery.

I have found in practice that by making the sides of the boot flaring—that is, by having them run slightly divergently from the rear end or portion of the boot toward the leading end—a sufficient clearance of all lumps which may gather between the sides of the buckets and those of the boot will be given to insure the ready escape or forcing forwardly and out of the way of such lumps without any injurious crowding of the lumps between the bucket and elevator sides.

My invention, hence, consists in an elevator-boot having sides which are flared apart or diverge from the vicinity of that portion of the boot into which the empty buckets descend toward the point at which the filled buckets pass out of the boot in an ascending direction, all as will be hereinafter more fully explained.

To enable those skilled in the art to make and use my invention, I will now proceed to more fully explain the latter, referring by letters to the accompanying drawings, which form part of this specification, and in which I have so far successfully used it, and which is the best now known to me.

In the drawings, Figure 1 is a side view of an elevator-boot made according to my invention, and Fig. 2 is a top view of the same.

In both figures the same part will be found designated by the same letter of reference.

The boot shown is made, as usual, of metal, with its bottom curved and extended up rearwardly and forwardly, so that it runs into the curved back and front ends, the latter and the bottom constituting a continuous curved surface of about the usual shape, as clearly shown at *b c d* in the drawings.

The two plain or flat side pieces, *A A*, of the boot are about vertical, as usual, and are located at their exterior surfaces in parallel planes, but have their inner surfaces slightly flaring or divergent from the rear of the boot toward its front, as clearly seen at *e f g* of Fig. 2.

In the side *A*, near their middles lengthwise, 100

are formed or arranged the usual casings, *i*, within which are held, laterally between ways, the adjustable boxes, in which are journaled the ends of the shaft *m*, that carries the 5 lower sprocket-wheel, *o*, of the elevator, and that is adjusted, in the usual manner, (to regulate the elevator-chain,) by means of the set-screw *p*, mounted suitably in the metallic stands or brackets *S*, bolted onto the tops of the sides 10 *AA* of the boot.

A reference to Fig. 2, which shows the flaring or divergent arrangement of the interior side walls of the boots, will make clear the fact that during the filling and escape of a series of buckets mounted on a chain (or other) 15 belt running over the wheel *o*, said buckets moving along within and passing up out of the boot in the direction indicated by the arrows, any lumps of coal or other material of irregular sizes and shapes that may happen 20 to get between the sides of the bucket (or either one of them) and the side walls of the boot (or either of them) will be rolled or crowded along in the general direction of motion of the bucket, or toward the forward end 25 of the boot, and will be pushed along in a space between the boot's walls and the bucket's sides that are of constantly-increasing capacity, and that therefore any such lump or 30 lumps of material will find a ready clearance or easy avenue of escape toward and into the most forward and widest part of the boot, from which said lump or lumps will naturally tumble backwardly and downwardly toward the 35 bottom of the boot, to be caught by and to fill into the successively-approaching empty buckets.

Of course in carrying out my invention it may be found expedient, under some circumstances, to make the sides of the boot so as to also spread apart slightly from the bottom toward the top of the boot; but I have not found this to be generally necessary in practice.

The degree of flare to the divergent side walls shown may be varied more or less, in 45 the judgment of the constructor of the boot, and according to the character of material to be handled by the boot and its elevator; but I have found the shape shown to embody a sufficient degree of flare in these side walls for all 50 practical purposes.

Much of the advantage due to my invention might be derived by having the side walls of the boot flared only from the vicinity of the point at which the buckets begin to turn and 55 fill within the boot toward the forward end, instead of from the extreme rear end of the boot to the front, as shown; but I have found the precise form and arrangement of flared sides to work well.

What I claim, broadly, as of my invention, and desire to secure by Letters Patent, is—

An elevator-boot having the interior side walls flared or divergent from the rear toward the leading end or front of the boot, substantially as and for the purpose set forth.

In witness whereof I have hereunto set my hand this 2d day of August, 1886.

JAMES M. DODGE.

In presence of—

D. S. GARWOOD,
EDWARD H. BURR.
